UNITED STATES PATENT OFFICE

170,855

THERMOSTATIC VALVE

Elton B. Fox, El Cerrito, Calif.

Application April 7, 1952, Serial No. 19,225

Term of patent 14 years

(Cl. D78—1)

To all whom it may concern:

Be it known that I, Elton B. Fox, a citizen of the United States, residing at El Cerrito, county of Contra Costa, State of California, have invented a new, original, and ornamental Design for a Thermostatic Valve, of which the following is a specification, reference being had to the accompanying drawings, forming a part hereof, wherein,

Figure 1 is a plan view of a thermostatic valve embodying my new design.

Figure 2 is a perspective view of the thermostatic valve showing the top and one side thereof.

Figure 3 is a side elevation of the thermostatic valve.

Figure 4 is a reduced sectional view thereof

taken on the line 4—4 of Figure 3, looking in the direction of the arrows.

The external portions of the three flanges not shown are conventional.

I claim:

The ornamental design for a thermostatic valve, substantially as shown and described.

ELTON B. FOX.
